UNITED STATES PATENT OFFICE.

EARL HEATH, OF MARINETTE, WISCONSIN.

BUILDING STRUCTURE.

1,416,821.

Specification of Letters Patent Patented May 23, 1922.

Application filed February 26, 1921. Serial No. 443,024.

To all whom it may concern:

Be it known that I, EARL HEATH, a citizen of the United States, residing at Marinette, county of Marinette, and State of Wisconsin, have invented new and useful Improvements in Building Structures, of which the following is a specification.

My invention relates to improvements in building structures.

10 It is the object of my invention to provide a building structure in which short lengths of timber, logs or post ends may be utilized with a minimum of mill work to construct a sturdy and serviceable building, 15 such for example as a silo, or log cottage having an outer surface conforming to the natural contour of the members of which the wall is composed.

In the manufacture of posts much valuable wood has usually been wasted. The trunks of cedar trees are cut to form telephone poles or other long posts from the lower portions, the smaller upper portions of the trunks being then cut to form fence 25 posts, but those portions which are too small or two irregular for fence posts are usually used only for fuel. It is one object of my invention to devise means for producing an inexpensive building material, as a by product of the post manufacturing industry.

Great quantities of small timber are also available in areas that are being logged or in areas that have once been cut over or logged. To mill such small timber has heretofore been expensive because when a small stick is cut into boards the amount of wasted material is proportionately much greater than is the case if large logs are being handled. It is therefore desirable, if this 40 small timber is to be used, to provide some means of using it without cutting it into boards, so that the waste and the labor involved may be minimized. It is the object of this invention to provide means of utilizing these small logs and pieces of logs, by devising a special type of building structure, peculiarly adapted to receive such material as nearly as possible in its natural condition, or in a condition into which it 45 may be reduced by simple machinery and with minimum labor and expense.

More particularly stated, my object is to provide means whereby short, irregular or small pieces of posts, logs or timber may be

cut into sets of pieces of uniform length 55 trimmed on two sides to allow them to be superposed to an approximate fit, recessed at their ends, and then laid up in block form either with, or without mortar, and anchored to vertical members or posts in such a manner as to produce a solid wall of great strength and durability, which can if desired be hooped or reinforced by bands of metal which find natural anchorage between the projecting portions of the members. 60 65

Embodiments of the invention are shown in the accompanying drawings, in which:

Figure 1 is an elevation of a building constructed for use as a silo in accordance with my invention, portions of the wall being 70 broken away on line 1—1 of Fig. 2 to expose constructional details.

Figure 2 is a cross sectional view taken on line 2—2 of Figure 1.

Figure 3 is a plan view of a stick or block 75 of wood prepared for use as a building unit in accordance with my invention.

Figure 4 is an end elevation of a pair of superimposed sticks of the sort illustrated in Figure 3. 80

Figure 5 is a plan view showing a modified form in which the building units to be used in my improved building construction may be shaped.

Figure 6 represents a pair of superimposed sticks of the form illustrated in Figure 5. 85

Figure 7 shows a building wall partly in section and partly in elevation embodying my invention in combination with a facing 90 of reinforced concrete or stucco.

Figure 8 is a plan view of the structure shown in Fig. 7, with a portion broken away in horizontal section.

Like parts are identified by the same reference characters throughout the several views. 95

While the building here shown is intended for use as a silo, I wish it understood that I do not limit my invention to buildings intended for that purpose. My improved construction will be found adaptable for many kinds of buildings. 100

The by-product material, i. e., pieces of logs or timbers heretofore wasted are cut 105 into sticks of substantially equal length, at least so far as any given section or superposed set of units is concerned. These units

are trimmed or cut away on opposite sides to form two parallel surfaces which for convenience in description are hereinafter referred to as the top and bottom surfaces.

5 The bark may or may not be removed from the other surfaces, and in any event these other surfaces, hereinafter referred to as the inner and outer surfaces, are preferably left in the natural contour of the log from which 10 the unit is formed. The ends of the units are cut in a plane oblique to the longitudinal axis where a generally circular structure is to be formed. By then placing two of the 15 units end to end, and holding them rigidly in position by means of a form or chuck it becomes possible to bore a hole through the abutting ends from top to bottom in such a manner as to produce substantially semi-cylindrical recesses in the ends. In this 20 manner, I produce a building unit or block 1, (Fig. 3), having substantially flat top and bottom surfaces 2 and 3, concave end recesses 4 and 5, and having front and rear surfaces of natural contour, these surfaces 25 being ordinarily convexly rounded from one end of the unit to the other, the axis of the curve extending longitudinally of the unit, whereas the axis of the concave recesses in the respective ends extends vertically.

30 Where the building to be erected is a silo or other building of a generally circular form, a series of posts 8, preferably mounted in a concrete base wall 9 with the ends imbedded or anchored in the concrete are suitably spaced to receive between them the sets 35 of units in such a manner that the sides of the posts are received in the concave recesses 4 formed in the ends of the units as above described. The units are therefore superimposed with their flat surfaces 2 and 3 in 40 contact with those of the units above and below them, whereby each section of the wall comprises a solid tier of blocks between the posts, and having their ends anchored to the 45 posts.

If desired, the surfaces 2 and 3 may be provided with longitudinal channels, such as the rectangular channels 10, shown in Figures 3 and 4, or the V-shaped channels 11 shown in Figures 5 and 6. These channels 50 are adapted to receive mortar or concrete. It is not essential to my invention that these channels be formed in both faces of each unit. It will ordinarily be sufficient to form 55 a channel simply in the upper face of each unit. In either case sufficient mortar can be placed in the channel of the unit which has been laid in position to allow the weight of the superposed unit to either flatten out the 60 mortar between the units or force it into the channel formed in the lower face of the superposed unit in cases where that unit is provided with such a channel. Mortar may of course also be forced into any spaces large 65 enough to receive it between the concave

ends of the units and the associated posts. But any material metallic or non-metallic, may be used in the channels to connect the units.

Obviously, very little mill work is necessary in making up the building units above described. Parallel saws or planing machinery can be utilized to cut the parallel surfaces 2 and 3 in one operation while the channel 10 may be made at the same time. 70 A large sized drill or a small rotary knife cutter can be used to cut away the ends of the units to form the semicircular vertical grooves 4 and 5. The units are milled or trimmed the same on both sides so that a 75 cut making the angular end 6 of one unit will also cut at the proper angle the end of the next unit to be taken from the same log so that when this next unit is turned over, it will be identical with the first. 80

The building units 1 having been prepared by the simple milling operation above described, are set between the posts 8 in tiers to form the walls of the building. For fastening together the superimposed building units or bolts 1, I employ two methods. 90 Where the grooves 10 are rectangular in cross section, as shown in Figures 3 and 4, a strip of lath or similar small piece of wood, shown at 12 in Figure 4, may be driven into the groove 10 of the lower unit and may then be received into groove 10 of the superimposed unit. The strips 12, used for this purpose, need not be dressed lumber and a wall so constructed will prove at once 95 economical and satisfactorily water tight and extremely substantial.

If the grooves 11 are of the form illustrated in Figures 5 and 6 a binding course of mortar or concrete may be laid between 105 the superimposed building units 1 and will enter grooves 10 or 11 rendering the structure even more completely waterproof than that made as shown in Figure 4. In fact, it is not absolutely necessary to provide the 110 units 1 with any grooves at all, for the interlocking construction whereby each unit is engaged between two uprights is extremely stable. The grooves merely aid in the retention of the mortar. Where a wa- 115 terproof structure is not necessary, no mortar will be required. It is immaterial to my invention whether the building units 1 be laid between the posts 8 in courses or whether the space between one pair of posts 120 is completely filled before the filling of the adjacent tier is begun.

Suitable openings 13 may be left at convenient points to be fitted with doors. Hoops 14 will preferably be used if the structure is 125 a silo, or in any structure where the vertical posts 8 tend to spread. The hoops will rest in the crevices between superimposed courses of building units and will thus be secured against accidental displacement, not- 130

withstanding shrinkage. The hoops will also draw into the crevices to a considerable extent if the building swells beyond its original size. The roof 15 may be of any 5 suitable form. If the roof is of such a nature as to bind together the tops of poles 8 there will be materially less need for the use of hoops 14, which will then be unnecessary except in particularly tall silos.

10 I have found that silos and other buildings constructed in the above described manner may be constructed at relatively small cost, because they permit of the use of timber that would otherwise be wasted and be- 15 cause the milling work necessary to prepare the building units 1 from such timber is very slight and can be done rapidly with the aid of few men.

Where the material composing the build- 20 ing units 1 is of small diameter, metal posts or rods may be substituted for the wooden posts 8 shown in the drawings. These posts not only take the place of the ordinary studding in buildings of common type, but 25 inasmuch as no nails or dowel pins are required to connect the units with the vertical members or posts it becomes immaterial whether the posts be formed of wood, metal, or concrete. Where exterior surfacing is re- 30 quired the spaces between the convexly rounded outer surfaces of the units provide ample anchorage for concrete or stucco, either with or without wire or other metallic reenforcement. It is therefore possible to 35 use a great deal of material which heretofore has been of no value, except as firewood and much of it of little value for that purpose where the wood is of a light quick burning type.

40 In Figure 7 the building wall is first formed as heretofore described with units 1 composed of small blocks or sticks of wood anchored to metal posts, dowels, or studs 16. The wall thus formed is enclosed by wire 45 netting 17 which may be used either with or without reinforcing bands or hoops, such as the hoops 14. This netting may be secured at intervals to the units 1 by staples, and a facing 18 of the concrete or stucco, 50 may then be applied to embed the wire netting and the material may be pressed into the spaces between the units 1, and into the spaces between the wire and the vertical posts 16, thereby securing firm anchorage 55 and ample support for the facing material, and also protecting the wood from decay and the metal from corrosion.

I claim:

1. A building wall comprising a series of 60 cylindrical vertical posts and interposed tiers of log units having their ends vertically recessed hemispherically to receive the posts and allow the front and rear portions of the ends of the units of adjacent tiers to abut, 65 the inner and outer surfaces of said log units

retaining their natural cylindrically rounded contour.

2. A building wall comprising tiers of horizontally disposed log units in abutting, end to end contact with those of the adjacent tiers, and cylindrical posts extending vertically across the axes of the logs at the joints between adjacent tiers and embedded in the respective ends of the logs forming such joints, said posts forming a concealed 70 doweling anchorage to connect the tiers with each other.

3. A building wall for utilizing the small ends of post logs and similar waste material comprising short log sections flattened on 80 two sides and arranged end to end in tiers of superposed units with their flat surfaces in contact and with the inner and outer surfaces cylindrically rounded in their natural unfinished condition, the abutting tiers hav- 85 ing cylindrical holes extending from top to bottom and cylindrical metal posts substantially fitting the holes and anchoring the tiers of units together.

4. A structure comprising a series of vertical posts equally spaced about a circle, a plurality of superposed log units of equal length arranged in tiers between the posts and interlocking therewith, said units having front and rear surfaces of natural con- 90 tour, and hoops adapted to encircle the structure between two successive courses, of 95 log units to prevent the posts and tiers of units from spreading or pushing outwardly under interior pressures.

100 5. A wooden structure comprising a series of vertical posts disposed in a circle, a series of tiers of superposed, substantially horizontal wooden blocks interlocked with said posts and having exterior convex surfaces of natural contour, and hoops encircling the posts and retained within the groove formed by the juncture of the naturally contoured surfaces of two successive courses of blocks.

105 6. A structure comprising a series of vertical posts, a plurality of elongated superposed horizontally disposed wooden log units vertically grooved at their respective ends to receive the posts, and having convexly rounded outer surfaces extending 110 along a horizontal axis between the posts, and a facing of non-metallic material covering the units and posts, and anchored between the convexly rounded surfaces.

115 7. A structure comprising a series of vertical posts, tiers of superposed horizontally disposed log units filling the spaces between the posts and formed to fit the contour of the faces of the posts at their respective ends with the posts partially embedded in the 120 ends of the units between their inner and outer surfaces, said units having cylindri- 125 cally curved outer surfaces of unfinished natural contour, a reinforcing net covering the outer faces of the units and posts, and a 130

non-metallic facing embedding the reinforcing net and anchored in the spaces between the units.

8. A building wall section composed of a column of horizontally extending superposed log units of small diameter and substantially equal length having natural rounded outer surfaces, and ends recessed along vertical lines a non-metallic facing covering the outer surfaces of said log units and anchored in the spaces between them, and vertically extending connecting mem-

bers interlocked in the recesses at the respective ends of the units and connecting them together in the column.

15

9. A building wall having an inner surface composed of tiers of horizontally disposed short cedar log units having their ends connected to those of adjacent tiers by vertically disposed dowel posts, and an outer covering of cementitious material, anchored in the spaces between the superposed log units.

20
EARL HEATH.
